UNITED STATES PATENT OFFICE.

DIGHTON A. ROBINSON, OF MINNEAPOLIS, MINNESOTA.

COAL-POCKET.

SPECIFICATION forming part of Letters Patent No. 622,018, dated March 28, 1899.

Application filed January 28, 1898. Serial No. 668,316. (No model.)

To all whom it may concern:

Be it known that I, DIGHTON A. ROBINSON, of the city of Minneapolis, county of Hennepin, State of Minnesota, have invented certain new and useful Improvements in Coal-Pockets, of which the following is a specification.

This invention relates to improvements in pockets designed especially for handling coal, though applicable for handling other material, such as ore or any kind of grain; and this invention is designed especially to cover certain improvements on the coal-pocket shown and described in the application of John Simpson, Serial No. 652,417, filed September 21, 1897.

In the drawings, Figure 1 is a side elevation of a coal-pocket embodying my invention, the pocket being represented in full lines as in its drawn-back or retracted position and its forward position being partially indicated by dotted lines. Fig. 2 is a side elevation, partially broken away, showing the hopper in its forward position and showing the extension turned down and the door open. Fig. 3 is a perspective view of the combined lock and brake.

In the drawings, 2 represents the body of the pocket, provided with suitable wheels 3 and 5 and supported upon suitable tracks, (indicated in the drawings by the dotted lines 7 and 9.) The manner of supporting the pocket and its mode of operation and general construction is the same as that of the pocket shown and described in said application of John Simpson.

For the purpose of conducting the coal to any desired distance from the end of the pocket and at the same time forming a reliable and convenient means for securing the door of the pocket I provide at the forward end of the pocket a trough-shaped apron or extension 10, pivotally supported on the pocket by means of a suitable pivot 11, one preferably arranged at each side of the pocket. This extension is adapted to be turned down into the position shown in Fig. 2, in which it forms an extension for the bottom of the pocket and conducts the coal from the pocket a distance equal to the length of the extension. Ledges 13 are provided at the inner end of the extension, and these when the extension is

turned down into the position shown in Fig. 2 strike against the flange 14 at the front end of the pocket. A sliding bolt 15 is provided upon the outer surface of the extension, and when the extension is turned up into the position shown in Fig. 1 this bolt engages a recessed lug 16 upon the front of the door 17, thereby locking the extension and the door and firmly securing the same into position. A cord 18 is connected to the bolt 15, and by means of this cord the fireman or attendant can release the bolt 15 and turn the extension outward from the position shown in Fig. 1 to the position shown in Fig. 2, although when the pocket has been brought into the position shown in Fig. 2 and the bolt 15 is released the weight of the coal in the pocket will ordinarily automatically turn the extension down into the position shown in Fig. 2.

I also prefer to provide a transverse partition 19, preferably hinged upon a transverse rod 20, passing through the pocket and provided at its lower end with a flange 21, adapted to rest against the bottom of the pocket when the partition is in an upright position. A rod 22 extends transversely beneath the pocket and is mounted in suitable bearings, in which it is capable of rotating. It is provided with an operating lever or handle 23 and has one or more lugs 24, adapted to extend through slots in the bottom of the pocket and to engage the flange 21 on the lower end of the partition 19. When the parts are in the position shown in Fig. 2, the partition will be locked, and only so much of the coal as is in front of the partition can escape from the pocket. When it is desired to release the coal in the rear of the partition, the lever or handle 23 may be raised, thereby depressing the lug 24 and bringing it out of contact with the flange 21. This will release the partition 19, and the coal will then fall by gravity under the partition.

I may use one or more of the partitions, if preferred, and may arrange such partition or partitions at any desired point or points in the pocket.

I also provide means for locking the pocket when it is drawn back or standing in the position indicated by full lines in Fig. 1, and I also provide a brake device by which the pocket may be stopped or held at any desired

point in its travel. A suitable beam or support 25 is arranged at a point near the rear end of the bucket, and suitable bearings 26 are provided thereon. A shaft 27 is mounted 5 in these bearings, and it is provided at one end with a crank-arm 28, having thereon a suitable weight 29. A cord 30 is connected to this crank-arm and extends to any convenient point, where it may be used by the fireman or attendant for the purpose of releasing the pocket. The shaft 27 is provided with a flattened portion 31, having a transverse hole 32 extending through it, and above this hole is a hook or dog 33. A rod 34 is pivoted to the 10 rear end of the pocket and extends through the opening 32 and is provided at its end with a suitable collar 35. This rod is also provided with a lug or shoulder 36, that is in position to be engaged by the hook or dog 33 when the 15 pocket is drawn back or stands in the position shown in Fig. 1. When this hook is thus in engagement with the projection or shoulder on the rod 34, the pocket is locked in position and cannot move forward until the hook is released from said lug. This is done by raising 20 the crank-arm 28 and turning the shaft 27 a sufficient distance to bring the hook out of contact with the lug 36. The pocket will then run forward; but it may be stopped at any 25 point in its travel by releasing the crank-arm 30 28, which causes the wall of the opening 32 to grip the surface of the rod 34 with sufficient force to hold the pocket at any point in its travel. This device may also be used for regulating the speed at which the pocket will 35 move forward.

As a safety device I also prefer to provide a chain 39, connected to the rear end of the hopper and to a suitable beam or support 40, 40 as shown in Fig. 1. This chain will act as a stop and prevent the pocket from running too far forward.

It will be understood that the form and mode of construction of the various parts may 45 be modified in many ways without departing from my invention, and I therefore do not

limit myself to the details of construction herein shown and described.

While the pocket herein shown and described is especially adapted for handling coal, 50 and particularly for coaling locomotives, I do not limit myself to its use for any particular purpose, as it may obviously be used for loading coal or other material into cars or into vessels or any other receptacle. 55

Having thus described my invention, I claim as new and desire to secure by Letters Patent—

1. The combination, with the movable pocket, of the rod pivotally connected to the 60 rear end of said pocket, and the rotatable brake-shaft through which said rod passes, for the purpose set forth.

2. The combination, with the movable pocket, of the rod pivotally connected to the 65 rear end of said pocket, and the pivoted hook or dog arranged to engage a lug or projection upon said rod when the pocket is in its retracted position, for the purpose set forth.

3. The combination, with the movable 70 pocket, of the rod pivotally connected thereto, the transverse rocking shaft, the weighted arm connected therewith, said shaft being provided with an opening through which said rod passes, for the purpose set forth. 75

4. The combination, with the movable pocket, provided with the rod pivotally connected thereto and having a suitable lug or projection 36 thereon, of the laterally-arranged shaft 27 provided with the opening 32, 80 the hook 33, the crank-arm 28, and the weight 29, said rod being arranged to pass through the opening in said shaft and the hook 33 being adapted to engage the lug 36 when the pocket is in its retracted position, for the purpose set forth. 85

In testimony whereof I have hereunto set my hand this 24th day of January, 1898.

DIGITON A. ROBINSON.
